Primary Examiner—Holly H. Baynham*Assistant Examiner*—Cynthia M. Chin(74) *Attorney, Agent, or Firm*—Quarles & Brady LLP(57) **CLAIM**

We claim the ornamental design for a radio remote control unit, as shown and described.

DESCRIPTION

FIG. 1 is a front side perspective view of a radio remote control unit showing our new design;

FIG. 2 is a rear side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.
